UNITED STATES PATENT OFFICE.

MARIA A. GILLILAND, OF ADRIAN, MICHIGAN.

TOWEL-RACK.

1,227,421.

Specification of Letters Patent.

Patented May 22, 1917.

Application filed September 24, 1915. Serial No. 52,445.

To all whom it may concern:

Be it known that I, MARIA A. GILLILAND, a citizen of the United States, residing at Adrian, in the county of Lenawee and State 5 of Michigan, have invented new and useful Improvements in Towel-Racks, of which the following is a specification.

This invention is an improved rack, especially adapted for use as an individual, sanitary 10 towel rack, for holding a number of towels, preventing the towels from coming in contact with one another and enabling any towel to be removed from the rack at any time without touching any of the other 15 towels, the object of the invention being to provide an improved towel rack of this kind for use in households, hospitals, offices and other places, and which is extremely cheap and simple, is strong and durable and is 20 slightly and pleasing in appearance.

The invention consists in the construction and arrangement of devices hereinafter described and claimed.

In the accompanying drawings:—

25 Figure 1 is a front elevation of a towel rack constructed in accordance with my invention.

Fig. 2 is an end elevation of the same.

Fig. 3 is a sectional view on the plane indicated by the line $a-a$ of Fig. 1.

30 My improved towel rack comprises a number of bars 1 and a bracket 2 to which the bars are connected, which bracket serves to support the bars, in spaced relation and to 35 arrange the bars at different elevations, so that the towels on the bars may be removed and replaced separately and without coming in contact with one another. The bars are of suitable length and the bracket is secured 40 to the center of the bars so that each bar is adapted to hold two towels, one on either end.

The bars are square, cross sectionally, and each has its ends upturned as at 3 and provided 45 with suitable knobs or balls 4. Owing to the cross sectional shape of the bars, each bar presents an edge 5 at its upper side and a pair of oppositely inclined, upper surfaces 6 which converge to said edge and combine 50 and coact with the edge to exert friction on a towel hung on the bar so as to prevent the towel from slipping, and hence tend to and

materially assist in holding the towel in place.

The bracket 2 has a base plate 7 provided 55 with openings 8 for the reception of securing screws whereby to fasten the towel rack to a door, wall, or other supporting object. The bracket also has a lower outwardly extending arm 9 which is preferably curved as 60 shown and a reversely curved and inclined arm 10 which extends from near the outer end of the arm 9 to the upper end of the bracket. The arms 9—10 are formed integrally and are also bent to form bearings 65 11 for the reception of the bars and to clamp the centers of the bars therein, each bearing being open at one side as at 12 and being provided with a set screw 13 for securely clamping it on the center of the towel supporting bar. Owing to the inclined arrangement 70 of the arm 10 the towel supporting bars are held in different vertical planes and at different elevations, with the innermost bar at the highest elevation so that any one of 75 the towels may be grasped at that portion which passes over the bar and removed from the bar without coming in contact with any of the other towels.

It will be understood from the foregoing 80 description that my improved rack is designed for use by a number of persons, such as the members of a household, so that each member of the household has his individual bar on the rack and his individual towel or 85 towels on said bar and that while all towels are held by the rack, so that any one of them may be readily and instantly removed or replaced, each towel is held distinctly and separately from all the other towels and prevented 90 from coming in contact therewith. Hence my improved rack is sanitary in a very high degree.

While I have herein shown and described a preferred form of my invention I would 95 have it understood that changes may be made in the form, proportion and construction of the several parts without departing from the spirit of the invention and within the scope of the appended claim.

Having thus described my invention, I claim:—

An individual sanitary towel rack comprising a bracket having an inclined arm

made of a single strip of material and provided with outstanding doubled portions forming non-circular bearings, towel supporting bars non-circular in cross-section and arranged in said bearings and held thereby and by said inclined arm in spaced relation, at different elevations and also in different vertical planes, and clamping means securing the doubled portions of said

inclined arm together and in mutual contact and also securing the supporting bars in said bearings. 13

In testimony whereof I affix my signature in presence of two witnesses.

MARIA A. GILLILAND.
